UNITED STATES PATENT OFFICE.

THOMAS B. ATTERBURY, OF PITTSBURG, PENNSYLVANIA.

FURNACE FOR MELTING GLASS.

SPECIFICATION forming part of Letters Patent No. 240,638, dated April 26, 1881.

Application filed March 26, 1881. (No model.)

To all whom it may concern:

Be it known that I, THOMAS B. ATTERBURY, of Pittsburg, county of Allegheny, State of Pennsylvania, have invented or discovered a new and useful Improvement in Furnaces for Melting Glass and for other Purposes; and I do hereby declare the following to be a full, clear, concise, and exact description thereof, reference being had to the accompanying drawings, making a part of this specification, in which—like letters indicating like parts—

Figure 1, Sheet 1, is a front central perspective view of my improved furnace, but with the left-hand end shown in longitudinal section in a plane immediately back of the front wall. Fig. 2, Sheet 2, is a transverse sectional view in the plane of the line $x^2 x^2$, Fig. 1. Fig. 3 is a like view in the plane of the line $x' x'$, Fig. 1, and Fig. 4 is a like view in the plane of the line $x^2 x^2$, Fig. 1.

My improved furnace is primarily designed and organized for the melting of glass; but some features of it are also applicable to furnaces designed for other uses wherein a high heat is required to be developed or generated in or over a chamber, working-bed, oven, or other space wherein any material to be heated or fluxed can be conveniently charged; but I will first describe its construction and operation as a glass-melting furnace. Thus considered, it belongs to the class of furnaces commonly known as "tank-furnaces," in which the ordinary glass-pots are dispensed with and the batch is charged directly into a tank, basin, or laterally-inclosed but open-topped receptacle, beneath an arch or roof, and wherein it is subjected to the action of an intense heat applied from above, somewhat as in the ordinary reverberatory furnace. In connection with such tanks or working-chambers I employ an improved construction of heat-generating apparatus, such as is adapted to give the temperature required for glass-melting purposes.

In the organization shown I employ, say, three working-chambers, of which two are shown at B and B', and a third one, B'', of like construction, is immediately back of the wall, wherein is shown, in Fig. 1, the charging and working hole D. The number of these working-chambers may be varied at pleasure, and each one is to have a charging and working

hole, D, or other suitable like openings, each of which is to be closed during the melting operation by a luted door or stopper, such as is well known in the art. These working-chambers are arranged side by side, with intermediate partitions or separating-walls, as shown, and they may be made of any desired shape and are built of suitable material.

A common roof, R, preferably arch-shaped in cross-section, extends over the several chambers. At each end of such a series of working-chambers I build a furnace, A, and in each furnace arrange the usual grate-bars, a, at one end, so that they shall extend beneath, say, one-half, more or less, (preferably a little less,) of the horizontal area of the fire and coking chamber A', and make a blank or close, or comparatively close, dead-floor, a', over or through the rest of such horizontal area. The object of this construction is to enable the fire or incandescent fuel to be temporarily pushed back from the grate-bars while the latter are being cleared of clinkers or other obstructions, after which it can be again drawn forward onto the grate-bars, or, if preferred, be allowed to remain back on the close floor a', where, more fuel being added, it may operate as a coking-fire, assuming that a carbonaceous gas-producing fuel is being employed. The fire and coking chamber A' is extended vertically upward, so as to form a reverberatory gas-combustion chamber, A'', surmounted by an arch, a'', which chamber A'' is above the horizontal level of the flues or passages which lead from the fire-chamber to the space beneath the roof and over the working-chambers. The combustible gases evolved from the fuel beneath pass up and circulate beneath the arch a'' in the chamber A''; but in order to insure and perfect their combustion so far as possible before they leave this chamber, I provide for supplying heated oxygen, either in the form of air or steam, to the gases, while in this chamber, and at a level above their level of exit. To this end, assuming air to be employed, I connect a pipe, P, of suitable capacity, with any suitable blower or blast apparatus, and from such pipe carry a pipe, p, to a flue, e, in the end wall of the fire-chamber, Figs. 1 and 4, which flue follows a zigzag course back and forth in such end wall any desired number of

times, with reference to the heating of the air therein to any desired temperature. The uppermost flue, e' , of this series is a little above the level of the passages which lead over to the working-chambers, as illustrated in Fig. 1, and from it a series of jet-holes, s , open into the elevated reverberatory chamber A^2 , so as to discharge heated jets of air therein, above the level of the line of draft therefrom.

10 The arch a^2 will take and retain a high temperature, and the eddies formed therein and the line of draft resulting from the several forces which act on the gases are such that much of the otherwise unconsumed gases are drawn up into this chamber, and are converted into heat and flame before escaping therefrom; but as some of the gases given off by the fuel will be likely to follow the direct route from the fire to the space above the working-chambers, I provide for the combustion of such while passing over the bridge-wall b . To this end I divide up the throat immediately above the bridge-wall by a series of pillars, b' , more fully shown in Fig. 3, but with sufficient spaces 25 b^2 between for the flow of the heat and flame from the heat-generating apparatus. Also, to supply heated oxygen at these points, I carry a branch pipe, p' , from the main pipe P to a flue, e , in the bridge-wall, and carry this flue back and forth in the bridge-wall, Fig. 3, such 30 number of times as may be necessary in order properly to heat the air, and the top flue, e' , of this series opens directly between the pillars b into the flue-spaces b^2 , so that the heated air, so introduced, shall be intimately intermixed with the unconsumed gases passing over; but in order to still further subdivide these air-jets, I prefer to lay a brick, s' , lengthwise across the middle of each air-escape port, 35 so that the air will escape through narrow slit-shaped openings s^2 into the passages b^2 ; but as considerable air may be required at these points, I provide another supply-flue, i , Figs. 1 and 4, which takes its supply from a branch, 40 p^2 , and passes through the end wall, thence across by the rear wall, and joins the flue e , as at i' , Fig. 3.

By the arrangement of flues thus described I secure a large and long heating-surface, and 45 an abundant supply of air subdivided in jets at the points where it will do the most good; but, as already suggested, the pipe P or one or more of the branches $p' p' p^2$ may be connected with a steam-generator, so as to supply 50 steam instead of air or steam mixed with air at the jet holes or openings, or steam at some and air at others. And it should be noted that the pillars b , by becoming highly heated, like the arch a^2 , facilitate the combustion of the 55 smoke and gases as they pass the bridge-wall, as well as confine the flow of such smoke and gases to paths directly over, as near as may be, the jet-openings s^2 .

A stack or chimney for carrying off the waste 60 products of combustion is represented at S , about midway between the ends of the compound furnace. Two currents of heat and flame,

one from each end fire-chamber, meet at or over the middle of the series of working-chambers, and in order that the heat shall act with like 70 uniformity on the contents of the middle tank as on the contents of the others, I provide two flues, $n n'$, Fig. 2, one, n , opening from the rear at or just beneath the spring of the arch, and the other, n' , rising from at or a little above the 75 same point in the front and passing over the roof, as shown. As a result of this the current or flow of heat and flame will be divided or distributed over the central working-chamber, B' , so as to secure in it equally good results as in the end ones.

It is a feature of some importance that I am enabled to control the heat or the generation of heat so perfectly as to adapt the apparatus to the varying temperatures required in glass 85 melting and working.

By a slide or other suitable form of damper or valve, n^2 , in the flue n' and like devices in the pipes $p' p' p^2$, as illustrated at v , I can brighten up a low fire to a great intensity 90 most instantly, and graduate it down with equal ease and certainty.

Other appliances and fittings, such as are usual or necessary in connection with furnaces of this class, are to be employed, and in particular I provide for each working-chamber a test-hole, z , closed by a slide or door, z' , Figs. 1 and 2, which hole extends down in a slanting direction, so that a rod may be inserted therein and into the glass in the tank for the 100 purpose of ascertaining or testing its condition. Also, to prevent the unpleasant escape of waste gases through the working-hole when the damper n^2 is closed, so as to deaden down the heat, I provide a vertical draft-flue, u , Fig. 105 2, immediately through the wall over each working-hole.

Some of the features of construction herein described may be advantageously used in other forms or styles of furnaces with substantially 110 a like operation, and all such uses I include herein as of my invention, and more especially is this true of the heat-generating apparatus shown and described.

This apparatus may be advantageously used 115 as a part of a metallurgic furnace, wherein an open-topped close-sided working-chamber is employed as a receptacle for the material to be heated, melted, or treated; and in the apparatus as applied to glass-making, the several 120 working-chambers may all be charged with "batch" simultaneously, and all worked outside simultaneously; but the better plan is to charge and work them in succession, one or more charges undergoing the melting operation 125 while the other previously-melted charges are being worked.

Also, as regards the use of two separate heat-generators discharging simultaneously currents of heat and flame toward each other 130 and over a working-chamber or chambers, I do not limit myself to any specific number of working-chambers, since advantageous results may be secured with only one working-cham-

ber and a furnace of the class described at each side or end of it; and by a heat-generating furnace of the class described, as I thus use the term, I mean one which involves in its construction and operation, not only a fire, but also a gas-combustion chamber outside the direct line of flow of the products of combustion as they would ordinarily go from the fire to the working-chamber flues.

10 I claim herein as my invention—

1. A pair of heat-generators, each embracing in its construction a gas-combustion chamber outside the direct line of draft from the fire to the working-chamber flues, in combination 15 with an interposed working-chamber or working-chambers, suitable for containing batch or other material to be heated, melted, or treated, and heat conduits or passages leading from such heat-generators toward each other over 20 such working chamber or chambers, substantially as set forth.

2. In combination with a series of two or more open-topped close-sided working-chambers, arranged in close proximity and beneath 25 a common roof or arch, a heat-generating apparatus at each end of the series, and heat and flame conduits thence to a common intermediate flue or flues, substantially as set forth.

3. A series of pillars, b' , built in the other- 30 wise open throat of a bridge-wall passage, in combination with a system of flues, $e e'$, in the bridge-wall, and jet-openings from the latter into the spaces b^2 between the pillars, substantially as set forth.

35 4. The gas-combustion chamber A^2 , arranged

immediately over the fire and coking chamber A' , without any intervening partition, having an arched roof and lying above the level of the passages leading thence to the working-chamber, substantially as set forth.

5. In combination with combustion-chamber A^2 , lying above the level of the passages leading therefrom, a system of flues, $c c'$, in the wall of the fire and coking chamber, and a series of jet-holes, s , opening into the chamber A^2 at a level above that of the exit flues or 45 passages, substantially as set forth.

6. In combination with end heat-generators, intermediate working-chambers, and communicating passages, a front and rear escape-flue, 50 $n n'$, substantially as set forth.

7. The combination of two end heat-generators, a series of two or more intermediate working-chambers subject to heat from the generators, a system of pipes for supplying oxygen to the combustion-chambers and bridge-wall throats, and a system of dampers or valves for controlling the oxygen supply through the pipes $p p' p^2$ and the escape through the waste-flue n' , substantially as set forth. 55

8. The slanting test-hole z in the wall of a tank glass-melting furnace, substantially as set forth.

In testimony whereof I have hereunto set my hand.

THOMAS B. ATTERBURY.
